COIN-OPERATED ELECTRIC SHAVER UNIT

Matt E. Ambler, San Diego, Calif.

Application January 14, 1955, Serial No. 33,981

Term of patent 14 years

(Cl. D52—3)

The characteristic features of the design reside in the full line portions.

I claim:

The ornamental design for a coin-operated electric shaver unit, substantially as shown and described.
